SMOKER'S COMBINATION APPARATUS

Charles B. Grady, Sky Top, Pa.

Application December 15, 1939, Serial No. 309,440

3 Claims. (Cl. 131—237)

This invention is a novel smokers' combination apparatus, such as is adapted to home, office or travel use by cigarette users, the word cigarette being intended to include cigars.

The general object of the invention is to afford a convenient and useful apparatus, adapted primarily to be placed upon a table or shelf, but in some instances adapted to stand upon the floor, which apparatus is simple and may be cheaply manufactured, and will present both interest and attraction in its use and appearance.

A particular object of the invention is to provide a combination apparatus having one or more or all of the following facilities, operations and conveniences: to embody an advantageous rest or support upon which to lay the cigarette during and after smoking; to provide an improved receiver for the ashes, in the nature of a small portable receptacle or box which either may be open or adapted to be closed by a lid; to combine therewith a convenient means of extinguishing a cigarette or its butt; to dispose of or divert the smoke from a cigarette or butt resting on the receiver thereby to eliminate annoyance; and to provide an apparatus having one or more of these functions in combination with utility as a lamp, which term is intended to include a lantern or other illuminated casing, column or shade.

In respect to the receiving of cigarettes and ashes the portable appliance hereof is safe, sanitary and easy to clean; the cigarette on its rest can burn away safely to ashes, and by easy manipulation the ashes and any short remnants of butts can be disposed of and put out of sight. With these advantages is combined the action of smoke disposal by the aid of a casing or lamp portion containing a smoke duct with its discharge directed from the user.

Further objects and advantages of the present invention will be explained in the hereinafter following description of practical embodiments of the invention or will be understood by those conversant with the subject. To the attainment of such objects and advantages the present invention consists in the novel smokers' apparatus, and the novel features of operation, combination, arrangement and construction herein illustrated or described.

In the accompanying drawings

Fig. 1 is a perspective view of a complete apparatus embodying the principles of the present invention, and showing the combination of the lamp or casing features with the receiver or appliance features.

Fig. 2 is a top plan view of the apparatus shown

in Fig. 1 with the lamp casing partly broken away.

Figs. 3 and 4 are two similar longitudinal vertical section views of the portable appliance or receiver of Figs. 1 and 2, respectively showing the same manually tilted in two directions to dispose of accumulating ashes.

Fig. 5 is a central vertical sectional view of the complete apparatus shown in Figs. 1 and 2 but with the receiver portion having been shifted to a position within the lamp or casing portion.

Fig. 6 is a transverse vertical section view of the receiver shown in Figs. 1 to 5, but with the removable shelf or tray portion separated upwardly from the box portion of the receiver.

Fig. 7 is a perspective view, partly broken away, of a receiver of a modified form, having a hinged lid or cover, shown open, and with snuffing or extinguishing means.

Fig. 8 is a longitudinal vertical section view of the receiver of Fig. 7, showing the lid closed and the cigarette extinguished; with a modification in the tray-supporting ledge.

The apparatus in its most complete form comprises the receiver or portable appliance 11 adapted to receive and hold cigarette and ashes, and the lamp or casing 12, shown in Figs. 1, 2 and 5 as a table lamp but which might be redesigned to stand on a floor. The structures of these cooperating elements, the lamp and the receiver, will be separately described in detail. In various figures are shown a cigarette C (intended to include a cigar), or its butt B, and the ashes A thereof, and the path of smoke S during disposal. Fig. 8 shows also a special snuffing means in the form of an extinguishing powder E, into which the lighted end of a cigarette or butt may be plunged for extinguishing it; this powder being preferably a chemical, such as baking soda, which it is found tends under heat to generate an extinguishing gas; and with this powder may be combined a suitable agent to neutralize the odor of tobacco tar or to perfume the surrounding atmosphere.

Describing first for convenience the lamp or casing 12, this is shown as comprising a hollow column 14, which may be the column of a lamp, and is shown of square contour. Through a pane or other transparent or translucent wall or shade 15 light may pass from an interior light or bulb 16, shown inserted in a light socket 17 suitably positioned by mountings 18 within the casing. The circuits are not shown, but a switch 19 is indicated for illuminating or turning off the lamp. The hollow lamp casing or column 14

operates as a stack to accommodate or afford a draft to carry away the smoke **S**, and a rising or natural draft is indicated as preferable. Preferably also the column is closed at the top, by the wall or cover **21**, and the circulation is through a draft entrance **22** near the bottom front of the casing, thence upwardly, and out by a rear smoke exit **23**. The base or bottom wall of the casing is extended frontwardly at **25** forming a level support or shelf to accommodate the receiver **11**, which may be placed between edge flanges **26** of the extension **25**, so that the receiver can be either located frontward of the casing while in active use, as shown in Figs. 1 and 2, or thrust inwardly as shown in Fig. 5 to bring the cigarette butt within the walls of the casing. In either position of the receiver the rising draft in the casing tends to suck upwardly the smoke and discharge it rearwardly near the top of the apparatus and therefore away from the smoker's face.

Referring next to the portable receiver **11**, this consists mainly of a box **30**, with side, end and bottom walls. It may be open at the top, but as shown in Figs. 7 and 8, may have a cover or hinged lid **31** adapted to stand upright and thereby serve as a screen or smoke baffle when open.

Within the receiver box is shown a tray **32**, in the nature of a shelf, positioned at an intermediate height well above the box bottom. The tray is shown as consisting of a floor **33** and side flanges **34**, the entire tray being preferably removably supported within the box, for example upon side ledges **35**, thus giving access for cleaning the box and tray. The tray or shelf, by receiving hot ashes and butt ends, keeps them above the box floor until cool, thus protecting the supporting table from injury by heat conduction through the box floor.

A characteristic feature is that the midshelf or tray **32** is somewhat shorter than the box, thus providing a descending passage **36**, preferably at one end only, by which, at will, ashes on the tray may be delivered downwardly to be received in an underneath compartment **37** concealed below the tray. If desired the ledges **35** may be formed at their ends with small upstanding projections **38** adapted to confine the inserted tray against endwise sliding within the outer box **30**.

To the extent thus described the appliance **11** serves as an ash receiver. To constitute the box a receiver for cigarettes or butts, it is provided with a rest **40** in the nature of an open support, preferably composed of cross bars or wires **41**, which are preferably mounted on the tray side flanges **34** at a substantial height above the tray floor, but somewhat below the level of the box top edges. In describing the cigarette rest **40** as composed of cross wires or bars **41**, these terms are intended to cover any thin members extending across, in spaced-apart relation, bridging the interior of the box from side to side. The spaced bars or wires **41** therefore constitute an effective support for a cigarette or butt, holding it suspended in the surrounding air where it may effectively burn out to ashes, while the tray bottom prevents any hot material from descending into contact with the box bottom. It will be noted that the rest wires **41** are preferably bowed downwardly, with a sagging contour, thereby better to hold a cigarette against accidental displacement, or blowing off the rest; and there is a clear space between the wires and tray bottom.

A particular spacing of the cigarette rest bars or wires **41** is shown, wherein a main group of wires has a fairly close spacing, to hold either a cigarette or short butt above the tray, but with another group, of one or more wires **42**, spaced sufficiently away from the others to afford a finger space **43**, leaving a gap in which the fingers may reach down for picking up a cigarette from the rest; the main group being spaced too closely to admit conveniently the fingers.

As a means of extinguishing a cigarette or butt laid upon the rest **40** there is shown in Figs. 7 and 8 a snuffing member in the form of blade or cutter **44**, mounted within the box lid **31** in such position that the blade will chop or cut off the lighted extremity of the cigarette, properly placed upon the cross wires, in the act of closing the box. In order to hold the cigarette down for this extinguishing operation the lid is shown provided also with a guard member **45** which comes down upon the cigarette, for example between the extreme two wires, and clamps it against tilting during the snuffing action, while the blade descends closely adjacent to the extreme wire.

The operation of the described structure has been indicated, and may be further explained as follows, showing that the objects and advantages first recited are afforded. The box **30** with tray **32**, arranged as described, constitute the novel ash receiver, the addition of the thin bars or rest wires **41** rendering it available also as a cigarette or butt receiver. A lighted cigarette laid upon the cross wires, constituting a rest, is suspended in air and readily burns out.

Figs. 3 and 4 illustrate the mode of disposal of ashes unduly accumulated on the tray. By picking up the receiver box and tilting it leftward the ashes are dumped from the tray through the passage **36** on to the floor of the box, as shown in Fig. 3, so that, by next reversely tilting the receiver, as shown in Fig. 4, the ashes may be caused to slide along into the concealed compartment **37**, disappearing from sight. The tray is now empty and ready for further use.

The embodiment shown in Figs. 7 and 8 is especially adapted for travel use since it may be tightly closed by its cover before packing away, thus preventing ashes and other contents from sifting out to the damage of other property.

The several described embodiments are well adapted for use in air conditioned enclosures wherein an excess air pressure is maintained. In such case the smoke from burning butts may be directed to openings or ducts which lead from the enclosure, the outgoing air stream carrying away the smoke.

The described extinguishing device **44**, **45** may be dispensed with since a cigarette butt may be snuffed out in other ways, for example by rubbing it against the rest wires **41** or upon the bottom of the tray or the box, or inserting it in the snuffing powder **E**.

The lamp and receiver elements described may be constructed of various materials, preferably of attractive finish or color. Sheet metal may be used, suitably finished, and with reflecting color and polish inside to promote illumination. Non-metallic materials may be used, as plastic or other compositions, with the lamp and receiver preferably matching in color. For a particularly inexpensive receiver, of the character shown, without lid and with or without tray, the walls may be composed of metal-coated cardboard, for example with a bright aluminum finish; so cheap

to manufacture is such a receiver for cigarettes and ashes that it would be practical to discard each receiver after a very few uses, making it available as a premium to be given away with a purchase of cigarettes or cigars.

There has thus been described a smokers' combination apparatus embodying the features of the present invention, both in relation to the complete combination of lamp or casing portion with receiver portion and as regards the features of each of said portions; and since many matters of operation, combination, arrangement and construction may be variously modified without departing from the principles hereof, it is not intended to limit the invention to such matters except to the extent set forth in the appended claims.

What is claimed is:

1. A light and portable cigaret and ash receiver comprising in combination, an oblong, freely portable and manually tiltable open-top box member adapted to be placed on a table and having a closed bottom and walls surrounding and closing the two sides and two ends; and a separate upwardly-removable interior oblong shallow tray member set down into position enclosed wholly within the box and substantially shorter than the interior length of the box and comprising a closed floor and upstanding side extensions and mounted permanently thereon in spaced relation elevated slightly above the tray floor, a cigaret rest consisting of spaced-apart cross-bars to support horizontally a cigaret suspended in air, the tray member being open-ended and having its floor smooth for the easy-sliding of ashes and butts endwise therealong towards and past the open end thereof; said box and tray members being mutually formed for the loose interior support of the tray member against longitudinal sliding in the box and with its floor at a predetermined elevation substantially below the top edge of the box and spaced substantially

above the bottom of the box thereby to leave a concealed but accessible receiving compartment between the box bottom and tray floor, whereby the tray may be bodily lifted out from and set back down into its interior position between the box end walls or replaced by a new tray within the box at will, thus facilitating thorough access and cleaning of both portable box and removable tray; and the relative shortness of the tray within the box leaving at one end a downward ash passage of substantial length and width between one end edge of the tray floor and an end wall of the box, whereby at will the entire receiver may be manually reversely tilted to cause the transfer of accumulated ashes and butts from the tray floor through the downward passage into the concealed compartment between tray floor and box bottom.

2. A cigaret and ash receiver comprising a portable open-top and flat bottom box, said box containing a cigaret rest comprising bars spaced apart upon which a cigaret may rest near the top level of the box, and a cover hinged to the box for opening and closing the same; together with means operated by the closing of the lid for snuffing a lighted cigaret or butt on said rest, comprising a cutter mounted in the lid in a position to descend adjacent to a rest bar thereby to remove the burning end of the cigaret, and a guard member operated by the descent of the lid to clamp down a cigaret between two rest bars.

3. A receiver as in claim 1 and wherein is a tray comprising a horizontal floor shorter than and located within the box and spaced between the box bottom and the cigaret rest in a position to catch and support the detached hot cigaret end, whereby the latter at will can be caused to descend from the tray floor to the box bottom beneath.

CHARLES B. GRADY.
